H. A. DOUGLAS

TERMINAL CONNECTER

Filed April 28, 1924

Inventor:
Harry A. Douglas

By G. L. Gray Atty

UNITED STATES PATENT OFFICE.

HARRY A. DOUGLAS, OF BRONSON, MICHIGAN.

TERMINAL CONNECTER.

Application filed April 28, 1924. Serial No. 709,569.

My invention relates to terminal connectors and provides improved means whereby wire conductors may be brought into firm mechanical and electrical union with 5 terminal contacts without the aid of solder and screws.

In carrying out my invention the terminal contact member is formed with a passage therethrough having angularly related portions which receive a conducting wire bent to conform to the passage and held in one branch of the passage by a surrounding element of the container, this surrounding element being preferably in the nature of a 15 metallic sleeve held within a carrier of insulating material.

The invention will be more fully explained in connection with the accompanying drawing in which Fig. 1 is a longitudinal sectional view of an electric coupling whose contacts are assembled with conducting wires in accordance with the preferred embodiment of the invention; Fig. 2 is a longitudinal view, partially in section of one of 20 the coupling members shown in Fig. 1; Fig. 3 is a sectional view on line 3—3 of Fig. 1; Fig. 4 is a longitudinal sectional view of another form of connector; and Fig. 5 is a 25 perspective view of one of the cylindrical metallic contact members.

Like parts are indicated by similar characters of reference throughout the different figures.

Each coupling member shown in Figs. 1 to 4 inclusive includes an insulating contact carrier 1 having, in Fig. 4, one bore 2 and, in Figs. 1, 2 and 3, two such bores. Each bore contains a cylindrical metallic sleeve or tubular element 3 having rims 3' engaging shoulders 2' each having a cylindrical bore, held tightly within the bore of the corresponding contact carrier. A cylindrical metallic contact member 4 is snugly received in the bore of each sleeve and has a sinuous passage formed with an intermediate portion 5 extending transversely therethrough and narrower longitudinal end portions 6 and 7 at the outside of and extending respectively toward the ends of this contact member. A wire 8 passes through said sinuous passage and is tightly engaged between the metallic sleeve and the cylindrical con-

tact member in the zones of the narrower end portions of the sinuous passage, the result being a very firm mechanical and electrical union of the wire with the contact member 4 to which it extends. 55

In the structure shown in Figs. 1 and 2, each of the contact members 4 of the left hand coupling member has a split and hollow plug continuation 9 and the members upon the other coupling member have socket continuations 10 which receive the plugs 9. 60

In the structure of Fig. 4 the contact member 4 of the left hand coupling member receives an inwardly sprung pressed contact 11 engaging the butt end 12 of the complementary contact. The carrier 1 for this latter contact is provided with two bayonet pins 13 receivable in bayonet slots 14 formed in 70 the shell 15 which permanently holds the left hand carrier. 65

In assembling the contact carriers with the contacts of my invention the wires are looped into the contacts before the contacts are assembled with the carriers whereafter the contacts are drawn into the bores of the carriers. 75

It will be observed that the cylindrical contour of each cylindrical contact member 80 is intact except at the end portions of the passage to enable engagement of the contact members with the enclosing sleeves in the zones of the ends of the passage.

It is obvious that changes may be made 85 without departing from the spirit of my invention.

Having thus described my invention I claim as new and desire to secure by Letters Patent the following:— 90

In a terminal connector, a carrier member having a bore, a contact member including a wire receiving portion adapted to be engaged within the bore in said carrier member, said wire receiving portion having a 95 wire receiving opening formed transversely therethrough intermediate its ends, and further having a pair of wire receiving recesses formed in opposite sides thereof, respectively, said recesses opening into said transverse opening at their inner ends and extending respectively in opposite directions longitudinally of said wire receiving portion from said transverse opening thereby to 100

provide in conjunction with said transverse opening a wire receiving passage of sinuous shape, the material of said wire receiving portion transversely opposite each of said recesses being extended transversely of said wire receiving portion beyond the base of the recess adjacent thereto for contact with

the wall of the bore in said carrier member to prevent tilting movement of the contact member within said bore.

10

In witness whereof, I hereunto subscribe my name.

HARRY A. DOUGLAS.
